CIRCULAR LOOM

Frank Corby Hale, Spondon, near Derby, England, assignor to Celanese Corporation of America, a corporation of Delaware

Application April 3, 1936, Serial No. 72,457
In Great Britain May 20, 1935

8 Claims. (Cl. 139—13)

This invention relates to circular looms of the type in which the shuttles are held in place within the warp sheds by means of rotatable vane wheels disposed outside the warp shed and adapted to pass through one sheet of the warps into contact with the shuttle, the threads of the sheet penetrated by the vane wheels passing between the vanes during relative rotation between the warps and the shuttles.

- 5 10 15 20 25 30 35 40 45 50 55
- 10 In circular looms in which the velocity of the shuttles in relation to the warps is great, as is necessary in order to obtain high output, and especially in looms employing delicate textile threads, it is highly important that in the event of damage to the warps or other occurrence likely to lead to warp jamming, weaving should be brought to an end with great rapidity so as to avoid the shuttles attempting to continue their relative motion with respect to the warps and stretching or breaking the jammed threads. Stop mechanism adapted to bring about rapid cessation of weaving by bringing the relative motion between shuttles and warps to an end irrespective of whether or not other motions incidental to the loom's working cease are described in U. S. Patents Nos. 1,822,292, 2,007,397, 1,968,041, 1,984,798, 2,019,608 and 2,027,459.

In looms in which the shuttles themselves rotate about the loom axis, the stop motion operates to apply a brake to the rotating member by which the shuttles, through the action of the vane wheels, are supported. The vane wheels themselves are rotated because of the rotation of this supporting member carrying gears in connection with the vane wheel shafts round the loom periphery and causing these gears to be driven by engagement with a toothed gear extending round the loom. Consequently, when the supporting member is brought to rest, the vane wheels also cease to rotate. Similarly, in looms in which the warps rotate, the stop motion may serve to put the supporting member into rotation, this resulting in the vane wheels slowing down until, when shuttles and warps are moving at the same speed, the vane wheels do not rotate.

It is an object of the invention to improve the vane wheel mechanism in circular looms of the type indicated.

According to the invention a free wheel mechanism is interposed between the vane wheels and the driving means for the vane wheels so as to make the vane wheels capable of overrunning the driving means. Consequently, when relative motion between the shuttles and the warps ceases, the vane wheels can continue their rotation.

Therefore, when the loom stop mechanism is called on to bring weaving to an end, the stop mechanism is relieved of the necessity for rapidly overcoming the momentum of the vane wheels themselves. Since the vane wheels in a multi-shuttle loom are both numerous and, because of their high speed of rotation, are possessed of considerable momentum, the invention enables relative rotation to be brought to an end in a much shorter space of time than if it had to overcome the rotation of the vane wheels themselves. Furthermore, by the vane wheels continuing their rotation the danger of the warps being stretched or broken by the vane wheels is lessened, in addition to the advantage in this direction due to the more rapid stopping of the shuttles.

The free wheel mechanism may be applied at any convenient point in the drive to the vane wheels, but preferably as near as possible to the point at which the vane wheel drive is derived from the loom drive, so as to permit not only the vane wheels to continue rotating, but also as much as possible of any gearing sharing in their rotation. For example, in a rotating shuttle loom of the type referred to above, the free wheel mechanism may be disposed close to the gears which are in driving connection with the toothed gear and the vane wheel shafts so as to allow of the greater part of the mechanism transmitting the drive to the vane wheels, as well as the vane wheels themselves, to continue rotating.

The invention will now be described in greater detail with reference to the accompanying drawings in connection with its application to different forms of vane wheel drive, the drawings showing several forms of free wheel devices.

In the drawings,

Fig. 1 is a front elevational view largely in section of the vane wheel driving mechanism for one shuttle;

Fig. 2 is a plan view corresponding to Fig. 1 showing the tangential disposition of the vane wheel shafts;

Fig. 3 shows to an enlarged scale a detail of Fig. 1;

Fig. 4 is a sectional view of an alternative form of vane wheel drive;

Fig. 5 is a detail of Fig. 4 in side elevation; and

Figs. 6 and 7 are two views of an alternative form of free wheel device suitable for use with the drive shown in Fig. 4, Fig. 7 being taken on the line 7—7 of Fig. 6.

The shuttles 1 are mounted for rotation along the normal line 2, the propulsion of each shuttle being effected by means of vane wheels 3 fixed on

a tangential shaft 4 mounted on columns 5 and carried on a ring 6 driven by any suitable means (not shown). The shafts 4 are connected by bevel gears 7, 8 to a shaft 9, the lower end 10 of which is provided with a gear wheel 11 meshing with a fixed gear, the pitch of the circle of which is shown by the dotted line 12. As the shaft-supporting ring 6 rotates round the loom, the gear 11 is carried round the gear 12 to rotate the shaft 9 and therefore the shaft 4 carrying the vane wheels 3.

The vane wheels are required to rotate at a high speed, this being effected by the large ratio between the gear 12 and gear 11, and also by the multiplying action of the bevel gears 8, 7. The vane wheels and the shafts 4 and 9 and the gears connected with the shafts acquire a high momentum. If, therefore, the shaft-supporting ring 6 is brought suddenly to rest to stop the rotation of the shuttles 1 about the loom, the connection of the gears 11 with the gear 12 causes the momentum of the rapidly rotating parts to resist the stopping action. In the arrangement shown, however, the effect of this momentum is substantially eliminated by making the lower part 10 of the shaft 9 separate from the main portion of the shaft, the main portion thus serving as an intermediate shaft between the lower driving or "geared" portion 10 and the vane wheel shaft 4.

As shown in greater detail in Fig. 3, collars 13 are provided a short distance from the approaching ends of the intermediate shaft 9 and the geared shaft 10, and between the collars the shafts are surrounded by a coiled spring 14 of such a diameter that it contracts itself on the shafts. The spring 14 is coiled in such a direction that during the anti-clockwise rotation of the geared shaft 10 as viewed in Fig. 2, the frictional engagement between the shaft and the spring tends to tighten the spring still further on the shaft, so causing the spring to turn with the shaft. The spring similarly tends to tighten itself still further on the intermediate shaft 9, thereby establishing a driving connection between the two shafts. When, however, the shaft-supporting ring 6 is brought to rest, the geared shaft 10 becomes stationary, and the continued rotation of the intermediate shaft 9 due to the momentum of this shaft and the shaft 4 carrying the vane wheels 3 together with the associated gears, drives the spring 14 in such a direction as to tend to release the grip of the spring coils on the shaft. Instead, therefore, of this momentum having to be overcome suddenly, there remains only the momentum due to the rotation of the vane wheels, shafts and associated gears about the axis of the loom.

When the intermediate shaft 9 ultimately comes to rest, the spring 14 automatically re-expands its grip, leaving the shaft 9 ready to be driven once more when the ring 6 is again set in motion. The gap 15 between the approaching ends of the shafts 9, 10 should be narrow enough to prevent the entry of a turn of the spring 14.

Referring now to Fig. 4, the shuttle 1 is propelled round the loom by vane wheels 3 mounted on a shaft 4 carried in a bracket 16 mounted on a rotatable shaft-supporting ring 17. The ring 17 is provided with a gear ring 18 driven by means of a gear wheel 19 on a shaft 20.

Helical gears 21, 22 connect the shaft 4 with a short radial shaft 23 terminating at its outer end in a gear 24 meshing with a stationary gear ring 25. Thus, during the rotation of the ring

17 the gear 24 is carried round the ring 25 to rotate the vane wheels 3 at a high speed.

The gear 22 is free on the shaft 23 and is provided with an internal ratchet wheel 26 with the teeth of which a pawl or pawls 27 engage. These pawls pass through a slot 28 in the shaft 23 and are pressed apart by means of a spring 29.

When the shaft 23 is driven by the gear 24 (clockwise as viewed in Fig. 5) the pawls 27 positively engage the teeth of the ratchet member 10 26 and so drive the gear 22 and the vane wheels 3. When the ring 17 is brought to rest the vane wheels 3 and their shaft 4 are free to over-run, the ratchet member 26 rotating idly round the pawls 27. The mechanism is thus freed from suddenly overcoming the momentum of the vane wheels 3 and shaft 4, leaving only the shaft 23 to continue its rotation.

If desired the free wheel device may be disposed at the end of the shaft 23 near the gear 24 so as to cut down to a large extent the momentum of this shaft also.

In the alternative form of ratchet device shown in Figs. 6 and 7, the ratchet mechanism is incorporated within the gear 22. A ratchet wheel 30 is secured to the shaft 23, and during the driving of the shaft 23 positively engages pawls 31 disposed internally of the gear 22 and pressed by springs 32 towards the ratchet wheel. When the shaft 23 stops suddenly, the pawls 31 over-run the ratchet wheel 30, thus allowing the vane wheels 3 to continue their rotation.

Having described my invention, what I desire to secure by Letters Patent is:—

1. In a circular loom in which rotatable vane wheels are provided to pass between the warp threads into engagement with a shuttle to position the shuttle within a warp shed, vane wheel driving means, and a free wheel mechanism interposed between said driving means and the vane wheels to make the vane wheels capable of over-running the driving means.

2. In a circular loom in which rotatable vane wheels are provided to pass between the warp threads into engagement with a shuttle to position the shuttle within a warp shed, a rotatable shaft for supporting and driving the vane wheels, driving means for rotating said shaft, and a free wheel mechanism interposed between said driving means and the shaft to make the shaft and the vane wheels capable of over-running the driving means.

3. In a circular loom in which rotatable vane wheels are provided to pass between the warp threads into engagement with a shuttle to position the shuttle within a warp shed, vane wheel driving means including a driving shaft, an intermediate shaft terminating at one end in substantial alignment with said driving shaft, and a coiled spring disposed around the aligned ends of the driving shaft and the intermediate shaft and adapted to tighten on the ends of said shafts to enable the driving shaft to drive the intermediate shaft in one direction, the spring being capable of slackening to permit over-running of the intermediate shaft and the vane wheel shaft and vane wheels.

4. In a circular loom in which rotatable vane wheels are provided to pass between the warp threads into engagement with a shuttle to position the shuttle within a warp shed, a ring between which and the warp threads there is relative circular motion with respect to the loom axis, a shaft carried by said ring and adapted to support and drive said vane wheels, a gear
